UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

WORK SHEET OR WEB FOR TYPEWRITING MACHINES.

Application filed July 19, 1923. Serial No. 652,486.

To all whom it may concern:

Be it known that I, JESSE A. B. SMITH, a citizen of the United States, residing in Stamford, in the county of Fairfield and State of Connecticut, have invented certain new and useful Improvements in Work Sheets or Webs for Typewriting Machines, of which the following is a specification.

The invention relates to webs, for use in typewriting machines, comprising a plurality of superposed plies, either disconnected or as a fan-fold, interleaved with carbons, and each ordinarily composed of serially arranged panels, writing areas or forms in registration with like or different forms on the other plies. More particularly, the invention relates to contrivances for using individual work-pieces, such for instance as blank checks and drafts, in connection with such a web, so that inscriptions typed upon such individual work-pieces may be recorded upon the several underlying panels or forms of the work-plies of the web.

An object of the invention is a contrivance whereby the web itself, and preferably the outer ply thereof, may be utilized as a means for holding such individual work-pieces in the machine, as well as for positioning the same for typing, and effecting line-space feed thereof, as the web itself is correspondingly moved around the platen.

The checks or other work-pieces may be individually inserted into and removed from the machine; and, in accordance with the present invention, may be individually secured to and removed from the web. For this purpose, after typing any desired entry thereon, a portion of the leading panel or form-section of the outer web-ply may be so severed from the rest as to leave a lip which overlaps the leading panel or form-section of the underlying work-plies, and outer carbon; and between which and the outer carbon or next underlying work-ply, one edge of the check or other work-piece may be inserted and held by friction or pressure.

The edge or portion of the work-piece thus inserted under the lip may be a part on which no typing is to be done, such for instance as the portion of a check on which the signature is subsequently to be made,

In this connection, it is a feature of the invention that the retaining lip may be formed by cross-cutting the leading panel or form-section of the outer work-ply on a horizontal line somewhat forward of the rear cross-boundaries of the underlying leading form-sections of the other work-plies; so that a pocket is provided into which the signature portion of the check may be slipped. It will be understood that, where the lip is formed by a cross-cut and removal of part of the outer work-ply, this operation may be performed after each form-to-form advance of the web on completion of typing on a form.

An object of the invention is the provision of means, and a method, whereby the more convenient downward insertion of the individual work-pieces, from above the printing line at the front of the platen, may be had in connection with a record-sheet, such for instance as the web referred to, normally fed around and under the platen from the rear thereof, and wherein the necessity of special mechanical devices, for holding and guiding the individual work-pieces, is obviated.

In this latter connection, it will be noted that once the individual work-piece is secured to the web above the printing line, whether by the cross-lip or by a marginal lip or by other means within the scope of the invention, the web may be given a reverse feed to bring the individual work-piece down to position for commencement of typing. When the cross-lip, referred to, is employed, the work-piece may be slipped down behind the same from a position at the front of the platen above the printing line.

A feature of the invention is the provision of means on the web, such for instance as the edge of the cross-lip, or a scoring, to serve as a gage for determining the proper setting of the individual work-piece with respect to the web.

Other features and advantages will hereinafter appear.

In the accompanying drawings, Figure 1 is a perspective view showing the web in position on the platen preliminary to removal of the leading part of the

outer web-ply to form the retaining lip for the individual work-piece.

Figure 2 is a view similar to Figure 1, showing an individual work-piece in the 5 form of a check in position on the web.

Figure 3 is a view similar to Figures 1 and 2, but showing the web and check moved to position for commencement of typing by reverse rotation of the platen.

10 Figure 4 is a view, in side elevation, of the platen and certain associated parts, with the web and check in Figure 2 position thereon.

15 Figure 5 is a plan view of a portion of the leading end of the fan-folded web, the plies of which have been made to lie side by side by unfolding the web.

20 Figure 6 shows a work-piece in the form of a blank check for use in connection with the web.

A machine in which the web may be used is that shown in United States Letters Patent to Wernery & Smith, No. 1,132,055, dated March 16, 1915, to which reference 25 may be had for a more complete understanding of the details thereof. In Figure 1, only the platen 10, the carbon-carrier 11, and a few other details are shown. The web 12, fan-folded to comprise plies 13, 14, 30 15 and 16, is led from the rear of the machine, through the carbon-carrier, to the platen-carriage (not shown), where it is turned down at 17 from the top of the usual rear paper-table (not shown) on the carriage, 35 and thence led around, under, and to the front of the platen, where it is brought upward across and above the printing line. The usual gage 18 on a staff 19, secured to the platen-frame (not shown), may be employed to determine the position of the 40 leading edge of the web for removal of the portion 20 of the outer web-ply in the formation of the lip 21, hereinbefore referred to.

45 It will be noted that the carbons 22 and 23 are secured at their rear edges to blades 24 and 25 on the carbon-carrier; and that the carbon-carrier is movable forward toward the platen on a table (not shown), to 50 permit of line-space and other movements of the carbons with the web-plies, and is movable rearward to shift the carbons, at the proper time, from the panels or form-sections of the web, which have been typed 55 upon, to the next succeeding or untyped panels or form-sections of the web. To permit of such shift of the carbons relative to the web-plies, the platen, as shown in the aforesaid Wernery & Smith patent, is on a 60 frame which may be rocked upward to release the grip of the platen on the web and permit the web to be drawn horizontally straight under the platen. A knife-blade 26, against which the web-plies may be 65 drawn for severance of the leading lengths

thereof, is also suitably mounted on the platen-frame. In Figure 1, this knife is shown as being utilized to sever the piece 20 of the outer web-ply in the formation of the lip 21.

As shown in Figure 5, the leading form-section of the web may be of greater width than the work-piece or check 27, and, as to the web-plies 14 and 15, for instance, may comprise two panels or forms, one of which is in advance of the panel or form-section which is to receive the inscriptions made upon the check. Consequently, prior to the removal of the part 20 of the outer web-ply, certain inscriptions 28 may be made thereon which will also be received, through the carbons, upon the other plies above the position in which the inscriptions made on the check are to be received. After the inscriptions 28, if any, are made, the part 20 of the outer ply is removed, leaving the back of the outer carbon 22 exposed to view. The lower portion of the check 27 (see Figure 2) is then slipped behind the lip 21, which constitutes the remaining portion of the leading form-section or panel of the outer web-ply. As shown in Figure 5, a scoring 30, which may be a mere mark, or which may be an indented or a perforated line, on each form-section of the outer web-ply, designates the line along which the outer web-ply is to be torn for removal of the part 20, and this line 30 may be used as a gage whereby to position the web with respect to the knife 26 for removal of the part 20. When the part 20 is removed, the line 30 defines the leading edge of the lip 21, as shown in Figure 2. A scoring 31 on each of the web-plies defines the boundary between the succeeding panels or form-sections of the plies; and the lines 31 on each of the plies are shown as in registration with each other. The lip may be considered as the strip on the outer ply between the lines 30 and 31 thereon. In positioning the check as shown in Figure 2, the edge 30 of the lip may serve as a gage; the correct position of the check being determined by registration of a line or mark, such, for instance, as the last writing line 32 on the check, with the leading edge 31 of the lip.

The check will ordinarily be held against displacement from its true inserted position with respect to the web-plies by the friction of the web-plies thereon. Guide-fingers 33, such as are usually employed in typewriting machines, may, however, by bearing upon the web, effect a pressure sufficient to prevent displacement of the check when the same is not held against such displacement by the usual pressure-rolls 34.

The check having been inserted as shown in Figure 2, the platen is given a reverse rotation to bring the web and check down to position for commencement of writing;

which, as shown in Figure 3, is the position in which the front-strike type-bars 35 will print the date at the top of the check. Thereafter the platen is line-spaced forward 5 with the web and check for typing in other positions thereon; and, if this forward feed of the check releases the same from the rolls 10 34, the guide-fingers 33 may, nevertheless, serve to prevent displacement of the check 15 with respect to the web, and to assure feed of the web and check as a unit.

In the operation of filling in the check, a copy of the check may be made on the ply 14, and different forms indicated on the plies 15 and 16 may be filled in with the same data. No writing will appear on the check below the leading edge 30 of the lip, but this portion of the check is, in any event, reserved for signature. If desired, however, typing, 20 which will not appear on the check or other work-piece 27, may be made on the lip, and will appear on the underlying web-plies 14, 15, 16, etc.

The check and underlying form-sections having been typed, the web, with the check, is advanced until the check may be lifted out of the pocket formed by the lip 21; and, thereafter, or without previous removal of the check, the web may be advanced until the 25 line 31 is brought to the knife-blade 26, and the leading panels or form-sections of the several web-plies, together with the lip 21, removed as a unit by drawing the same against the knife. Before such severance of 30 the leading form-sections of the web at the line 31, the carbons will, however, have first been withdrawn into the next succeeding form-section of the web by suitable means, such, for instance, as shown in the Werner 35 & Smith patent, above mentioned. The operations heretofore described are again repeated for the succeeding form-sections of the web and for the typing of other checks.

It will be noted (see Figure 1) that the 40 usual blade on the carbon-carrier 24 serves to split the outer work-ply 16 from the next underlying work-ply 15, along the line on which the two are folded, as the web is fed forward through the carbon-carrier; so that, when the web is in Figure 1 position, the portion 20 of the outer ply is disconnected 45 from the next underlying ply, and is ready for severance along the line 30, as hereinbefore set forth.

Variations may be resorted to within the 50 scope of the invention, and portions of the improvements may be used without others.

Having thus described my invention, I claim:

1. A web for use in a typewriting machine, comprising, superposed work-plies, and interleaved carbons; the outer work-ply being scored at intervals therealong for successive detachment of leading sections therefrom at such points thereof as to provide,

when such a detachment is made, a lip overlapping a more forwardly-extended panel or writing area of the underlying work-plies and carbons, for holding in typing position over such panel, and by the rear edge thereof, a workpiece such for instance as a blank check or draft. 70

2. A web for use in a typewriting machine, comprising, superposed work-plies, and interleaved carbons; the outer work-ply 75 being scored at intervals therealong for successive detachment of leading sections therefrom at such points thereof as to provide, when such a detachment is made, a lip overlapping a more forwardly-extended panel or writing area of the underlying work-plies and carbons, for holding in typing position over such panel, and by the rear edge thereof, a work-piece such for instance as a blank check or draft; and such outer ply being 80 further scored in registry with the cross boundaries of the panels or writing areas of the underlying work-plies. 85

3. A web for use in a typewriting machine, comprising, superposed work-plies, 90 and interleaved carbons, shiftable along the work-plies from one to another panel or writing area of the work-plies; the outer work-ply being scored at intervals therealong 95 for successive detachment of leading sections therefrom at such points thereof as to provide, when such a detachment is made, a lip overlapping a more forwardly-extended panel or writing area of the underlying work-plies and carbons, for holding in typ- 100 ing position over such panel, and by the rear edge thereof, a work-piece such for instance as a blank check or draft. 105

4. A web for use in a typewriting machine, comprising, fan-folded work-plies, 110 and interleaved carbons; the outer work-ply being scored at intervals therealong for successive detachment of leading sections therefrom at such points thereof as to provide, when such a detachment is made, a lip overlapping a more forwardly-extended panel or writing area of the underlying work-plies and carbons, for holding in typing position over such panel, and by the rear edge thereof, a work-piece such for instance as a blank 115 check or draft.

5. A web for use in a typewriting machine, comprising, superposed work-plies, carbons interleaved with the work-plies, a 120 lip formed on the outer work-ply, crosswise thereof, by detachment of a leading portion of such outer ply, and a work-piece removably held in place on the web by location of its edge between such lip and an underlying 125 ply of the web.

6. A web for use in a typewriting machine, comprising, superposed work-plies, carbons interleaved with the work-plies, a lip formed on the outer work-ply by detach- 130 ment of a leading portion of such outer ply,

and a work-piece removably held in place on the web by location of its edge between such lip and an underlying ply of the web, the lip being so located that its edge may serve 5 as a gage whereby to position the removable work-piece on the web.

7. A web for use in a typewriting machine, comprising, superposed work-plies, carbons interleaved with the work-plies, a 10 lip formed on the outer work-ply, crosswise thereof, by detachment of a leading portion of such outer ply, and a work-piece removably held in place on the web by location of its edge between such lip and an under- 15 lying ply of the web; the removable work-piece having a scoring thereon for registration with the edge of the lip to gage the

position of the removable work-piece on the web.

8. A web for use in a typewriting machine, comprising, superposed work-plies, carbons interleaved with the work-plies, a 20 lip, and a work-piece removably held in place on the web by location of its edge between such lip and an underlying ply of the 25 web, the lip being of such depth and the position of the removable work-piece being such that space for signature or other writing is provided on the portion of the removable work-piece under the lip.
